APPARATUS FOR SIMULTANEOUSLY TWISTING AND WINDING YARNS OR THREADS INTO COPS

William Thomson Brand and Eric John Fairweather, Dundee, Angus, Scotland

Application September 27, 1935, Serial No. 42,546
In Great Britain September 29, 1934

4 Claims. (Cl. 117—27)

This invention relates to apparatus for simultaneously twisting together a plurality of yarns or threads and winding the same into a cop or the like.

5 Apparatus according to the invention comprises a rotary cup or cone or equivalent structure coaxial with an axially movable spindle, and rotating yarn guides, one carried by said structure and one deriving traversing movements from 10 a cam whose axis lies on the axis of rotation of said structure, the assembly being such that a plurality of yarns or threads led through said guides to said spindle are simultaneously twisted together and built into a cop or the like.

15 The cam is suitably formed as a sleeve having an internal cam groove.

Fig. 1 of the accompanying drawing is a sectional elevation of apparatus according to the invention. Fig. 2 is a fragmentary elevation of 20 the cone and reciprocating bar shown in Fig. 1. Fig. 3 is a fragmentary elevation, partly in section, of a modified form of cone and Fig. 4 is a plan view corresponding to Fig. 3.

As illustrated by Figs. 1 and 2, the yarns 1 25 (two or more) to be twisted together and wound into a cop are led from the customary final retaining or drawing roller or rollers over a tensioning device (not shown), to a guide 2 or the like attached, by means of an arm 3, to a revolving cone or cup 4 coaxial with the spindle 5 on which the cop 6 is to be formed.

Conveniently, the cone 4 is rotated by means 35 of a spiral gear 7 secured on a shaft 7' and meshing with a spiral gear 8 on a depending sleeve 9 forming an extension of the cone 4 and embracing the spindle 5. The spiral gear 7 also meshes with a spiral gear 10 mounted on a shaft 21 and meshing in turn with a spiral gear 11 coaxial with the spindle 5 and unitary with a socket 15 within which is secured a sleeve 12 formed with an internal cam groove 13.

A bar 16 received in a groove 18 formed in the outer face of the cone 4 is provided with a follower 17 which tracks the cam groove 13 whereby 45 rotation of the sleeve 12 imparts endwise reciprocating movement to the bar 16.

19 denotes a slot formed in the upper end of the grooved portion of the cone. 20 denotes a yarn guide provided at the upper end of the bar 16.

In operation, the gear 10 drives the gear 11 and therefore the sleeve 12. The gear 7 drives the gear 8, the sleeve 9, and the cone 4. The cone 4 and sleeve 12 rotate at different speeds. The cam groove 13 reciprocates vertically the bar 16 and therefore the yarn guide 20. The yarns 1 pass through the guides 2 and 20, and, having been twisted, are built on the spindle 5, the vertical movement of the bar 16 imparting traversing movements to the guide 20.

The spindle 5, which is not driven, is supported by a footstep bearing 22 carried by a lever (not shown) which may be actuated by the foot of the operator when it is desired to move the spindle endwise.

5 During the operation of twisting the yarns and building the cop, the spindle 5 rises, the lever swinging on its fulcrum. The lever may be provided with an adjustable spring or counterweight, so that different sizes and/or qualities of yarns 10 may be tightly wound into a cop.

Rotation of the spindle 5 is resisted by the action of a suitable drag device 23.

Preferably, the depending extension 9 of the cone 4 is mounted in ball bearings 24 located 15 above and below the machine rail 25.

According to the embodiment of the invention illustrated by Figs. 3 and 4, there are substituted for the cone 4 three spaced conical rollers 26 which are mounted between a ring 27 and a 20 sleeve 28 which corresponds to the lower part of the sleeve presenting the cup 4 of the embodiment shown by Figs. 1 and 2 and which is embraced by the sleeve 12. The ring 27 is supported by three spaced stay rods 29 and is provided with a yarn guide 2. The groove 18 in which reciprocates the bar 16 is formed in the outer surface of the sleeve 28. The yarns pass from the guide 2 to the guide 20 carried by the upper end of the bars 16 and are wound into a 30 cop on the spindle 5 which passes centrally through the ring 27 and sleeve 28, the operation being similar to the operation described with reference to Figs. 1 and 2.

Any suitable stop motion device may be fitted. 35

What we claim is:—

1. Apparatus for simultaneously twisting together a plurality of yarns or threads and winding the same into a cop or the like, comprising a rotary cop-receiving structure, an axially movable spindle coaxial with said structure, and rotating yarn guides, one carried by said structure, and a cam for imparting traversing movements to the other of said guides, the axis of said cam lying on the axis of rotation of said structure. 45

2. Apparatus as claimed in claim 1 in which the cam is formed as a sleeve having an internal cam groove.

3. Apparatus as claimed in claim 1 in which a spiral gear on a driving shaft drives a spiral 50 gear secured to the cam, said shaft driving also a second shaft which drives the rotary structure through spiral gearing.

4. Apparatus as claimed in claim 1 in which the rotary structure is constituted by conical 55 rollers assembled round the spindle at spaced intervals with their axes inclined to the spindle.
